FURRING CLIP

Sidney J. Radeke, Ann Arbor, Mich.

Application February 18, 1946, Serial No. 648,264

10 Claims. (Cl. 72—118)

1

The invention relates to the furring of masonry walls to form a support for the plastered inner wall and to leave an air space therebetween.

It is the object of the invention to accomplish this furring by the use of metallic clips of peculiar construction and to this end the invention consists in the construction as hereinafter set forth.

In the drawings:

Fig. 1 is an elevation of the slotted blank from which a plurality of clips of different specific constructions may be formed;

Figs. 2, 3 and 4 are perspective views of different clips formed from the blank;

Fig. 5 is a horizontal section showing the clip as attached to a masonry wall and supporting plaster boards spaced from said wall;

Fig. 6 is a vertical section of Fig. 5;

Figs. 7 and 7A are sections on line 7—7, Fig. 2, respectively before and subsequent to the driving of the securing nail therethrough;

Fig. 8 is a horizontal section showing the specific clip of Fig. 4 as applied to an inner corner of the masonry wall;

Fig. 9 is a similar view of the clip shown in Fig. 3 as applied to an outer masonry wall.

In the furring of masonry walls it is usual to use wood strips secured to the inner face of said wall and to which the lathing for the plaster wall is nailed. There are various objections to this construction such as the shrinking and swelling of the strips due to different moisture conditions and also twisting and buckling, all of which disturb the plaster wall. Furthermore, the wood strips interrupt the air space between the plaster and the masonry wall. With my improved construction these objections are overcome and various other advantages are gained.

The clips are preferably formed of sheet metal and in case sheet steel is used, are suitably rust-proof. The sheet metal blank A is of rectangular form and is laterally slotted on opposite sides of a central portion thereof. Preferably there are four pairs of slits A', A², A³, A⁴, which extend from the opposite edges inward but leave a central unslotted portion A⁵. This divides the blank into five pairs of separately bendable tongue portions, the central pair A⁶ being wider than those on opposite ends thereof. There is also a nail receiving aperture A⁷ at the center of the blank. Where the clip is to be used on a straight masonry wall, it is fashioned into the form B, shown in Fig. 2. The upper and lower pairs of tongues are bent to have outwardly extending portions B' and laterally extending por-

2

tions B². The tongues next adjacent to the end pairs are left in the original plane and thus are spaced from the portions B² by a dimension equal to the thickness of the plaster board. The central tongues are bent to form portions B³ which lie adjacent to each other and are perpendicular to the original plane of the blank. These portions are attached to each other by suitable means, such as spot welding or riveting, at points B⁴ on opposite sides of the center. To attach the clip to the masonry wall the portions B⁴ are placed against the wall and a nail, such as C, is engaged with the aperture A⁷ and driven inward spreading the center of the portions B³ to pass therebetween and into the wall. These portions B³, therefore, form a reinforcement for the nail that holds the same from bending. The plaster board sections may then be placed between the portions B² and the next adjacent tongues B⁵ which are in the original plane.

To form an inside corner the construction D, shown in Fig. 4, is used. This is formed from the same blank A but the central tongues A⁶ are bent at an angle of 45° to the original plane on opposite sides of the portion A⁵ to form portions D' at right angles to each other. The next adjacent tongues D² are bent at an angle of 45° to the original plane but oppositely from the portions D'. The end tongues have portions D³ bent parallel to and in the same plane as the portions D' and are rebent to form portions D⁴ which are parallel to the portions D² but spaced therefrom by the dimension of the portion D³. In applying this to the corner as shown in Fig. 8, the portions D' are placed against the two walls of the corner and a nail is driven through the aperture A⁷ into the corner of the masonry wall. The plaster board sections are then placed between the tongues D² and D⁴ and are held thereby.

The construction E, shown in Fig. 3, is applied to an outer corner of a masonry wall. This construction is formed from a slotted blank, such as A, but slightly modified in that the slits A' and A³ are shorter extending only to the points A⁸, Fig. 45. 1. The portions centrally between the slits A' and A⁴ of the blank are bent at an angle of 45° to the original plane to form portions E' which extend at right angles to each other. The portions E² between the shorter slits A' and A³ are bent at right angles to the portions E' which brings them also at right angles to each other. These portions E² contact against the masonry wall on opposite sides of the corner and space the portions E' therefrom. The end tongues of 50 the blank are bent in the same manner as in the

construction of Fig. 4 so as to form similar spaced tongues E³ and E⁴ for engaging opposite faces of the plaster board sections. Thus, all three constructions illustrated in Figs. 2, 3 and 4 are formed from a slotted blank, which is substantially the same being modified only in shortening the slits A' and A⁴ for the construction of Fig. 3.

What I claim as my invention is:

1. A clip for holding a wall board spaced from a supporting wall comprising a sheet metal blank laterally and parallelly slotted upon opposite sides of a central portion thereof to form a plurality of pairs of tongues, certain of said tongues being offset from but parallel to the original plane to embrace between the same and other of said tongues in said plane the wall board, and still other of said tongues being bent to extend perpendicular to the aforesaid tongues and the supporting wall into contact with the latter.

2. A clip for holding a wall board spaced from a supporting wall comprising a sheet metal blank laterally and parallelly slotted on opposite sides of a central portion thereof to form a plurality of pairs of tongues, certain pairs of tongues on opposite ends of the central pair being offset from but parallel to the original plane to embrace between the same and other tongues in said plane a wall board, and said central tongue extending perpendicular to the aforesaid tongues and the supporting wall into contact with the latter.

3. A clip for holding a wall board spaced from a supporting wall comprising a sheet metal blank laterally and parallelly slotted on opposite sides of a central portion thereof to form a plurality of pairs of tongues, the opposite end pairs of tongues being offset from but parallel to the original plane to embrace between the same and the adjacent pairs of tongues in said plane a wall board, and a central pair of tongues being bent to extend perpendicular to the aforesaid tongues and the supporting wall into contact with the latter.

4. A clip for holding a wall board spaced from and attached to a supporting wall comprising a sheet metal blank laterally and parallelly slotted on opposite sides of a central portion thereof to form a plurality of pairs of tongues, certain of said tongues being offset from but parallel to the original plane to embrace between the same and other of said tongues in said plane the wall board and still other of said tongues being bent to extend perpendicular to the aforesaid tongues and the supporting wall into contact with the latter, and securing means extending through a central aperture in said clip into said supporting wall.

5. A clip for holding a wall board spaced from and attached to a supporting wall comprising a sheet metal blank laterally and parallelly slotted on opposite sides of a central portion thereof to form a plurality of pairs of tongues, certain of said tongues being offset from but parallel to the original plane to embrace between the same and other of said tongues in said plane the wall board and still other of said tongues being bent to extend perpendicular to the aforesaid tongues and the supporting wall into contact with the latter, and a securing nail extending through a central aperture in said clip into said supporting wall.

6. A clip for holding a wall board spaced from and secured to a supporting wall comprising a sheet metal blank laterally and parallelly slotted on opposite sides of a central portion thereof to form a plurality of pairs of tongues, certain of said tongues on opposite ends of the central pair of tongues being offset from but parallel to the

original plane to embrace between the same and other tongues in said plane the wall board and said central pair of tongues being bent to extend perpendicular to the aforesaid tongues and the supporting wall into parallel contact with and secured to each other, and a nail passing through a central aperture in said clip and in the plane between said contacting tongues and into said supporting wall thereby spreading said tongues for its passage therebetween and being reinforced thereby.

7. A clip for holding a pair of wall boards spaced from a supporting wall on opposite sides of a corner therein comprising a sheet metal blank laterally and parallelly slotted on opposite sides of a central portion thereof to form a plurality of pairs of tongues, certain pairs of tongues on opposite end of a central pair being offset from but parallel to the original plane to embrace between the same and other tongues in said plane a wall board said central portion being bent with the members of the pairs on opposite sides thereof extending at an angle to each other, the tongues of the central pair being bent to extend perpendicular to the aforesaid tongues which are on the same side of the center and respectively into end contact with the supporting walls on opposite sides of the corner.

8. A clip for securing wall boards parallel to and spaced from a supporting wall, comprising a rectangular sheet blank slotted from and perpendicular to one edge thereof to form a plurality of pairs of tongues on opposite sides of a central tongue, one tongue of each pair being offset to embrace between the same and the adjacent tongue of the pair a wall board, and said central tongue being bent to extend perpendicular to said board to form a spacer between the same and said supporting wall.

9. A clip for securing wall boards parallel to and spaced from a supporting wall, comprising a rectangular sheet blank slotted from and perpendicular to opposite parallel edges thereof leaving an unslotted portion in the center, each of said slotted portions forming pairs of tongues on opposite sides of a central tongue, one tongue of each pair being offset from the original plane to embrace between the same and the adjacent tongue in said plane a wall board, and said central tongues being bent to extend perpendicular to said board to form a spacer between the same and said supporting wall.

10. A sheet metal clip for holding wall boards spaced from a supporting wall, comprising a narrow central portion and series of successively adjacent tongue portions projecting laterally from opposite sides of said central portion and integral therewith, certain of said tongue portions being offset from others into parallel planes to embrace wall boards therebetween, and other of said tongues being bent transversely to form a spacer between the wall board embracing tongues and the supporting wall.
